UNITED STATES PATENT OFFICE.

WALTER WURST, OF BERLIN, GERMANY, ASSIGNOR TO GESELLSCHAFT FÜR DRAHTLOSE TELEGRAPHIE M. B. H., BERLIN, GERMANY, A CORPORATION OF GERMANY.

ARRANGEMENT FOR TWO-WAY TELEPHONY.

Application filed November 23, 1923, Serial No. 676,489, and in Germany December 2, 1922.

It is known that a vacuum tube transmitter, for instance, in the so-called "three-point" connection, can be used as a receiver when the receiving telephone is inserted 5 directly in the plate-filament circuit or is connected to it by means of a transformer. This three-point connection is a particular 10 form of regenerative connection for a three element vacuum tube, and is illustrated in the embodiment of the invention disclosed in this application merely to exemplify one of many available regenerative circuits. This arrangement has the disadvantage that the speech transmitted by it, which for the 15 sake of convenience will hereinafter be sometimes referred to as the transmitted speech, is reproduced with extreme loudness in the receiving telephone. Therefore, such an arrangement is very objectionable, particularly when the same wavelength is used for simultaneous transmission and reception. It is necessary 20 to diminish the loudness in the receiving telephone of the transmitted speech without diminishing the loudness of the received speech. According to the invention, this 25 aim is accomplished by the provision of means for limiting the current which may pass through the receiving telephone, and in the event that the receiving telephone is connected to the plate-filament circuit of the 30 vacuum tube by means of a transformer, such means may be constituted by a current-limiting device inserted between the receiving telephone and the transformer. The 35 current-limiting device regulates the maximum current in such a way that the loudness of the transmitted speech in the telephone is kept within small limits at will. At the same time, the current-limiting characteristic 40 of the device is so chosen that the strength of weak speech is not diminished. The current-limiting device may, for example, comprise a three-electrode vacuum tube, the speech-transformer acting upon the grid and the receiving telephone being inserted in the plate-filament circuit of the tube. The filament-heating current of the current-limiting vacuum tube can easily be 45 regulated in such a way that the effect of the transmitted speech on the receiving telephone is sufficiently weakened. If the current-limiting tube is caused to operate at the

steepest point of its characteristic curve, an amplification of weak, received signals may 55 also be attained.

In the drawing,

Fig. 1 is a diagrammatic representation of a circuit arrangement embodying the invention; and

Fig. 2 is a diagrammatic representation of a circuit arrangement also embodying the invention and utilizing an additional vacuum tube as a current-limiting device.

Referring to Fig. 1, *a* denotes an electron discharge device having a hot cathode *k*, a cold anode *d* and a cold control electrode *s*, all enclosed within an evacuated envelope, as is well known in the art. This tube has its circuits connected up regeneratively to 70 generate sustained oscillations for transmitting purposes. The mode of regenerative connection shown is known in the art as a "three point" connection.

The circuit which determines the frequency of the generated oscillations comprises an inductance 1 and a capacity 2. The filamentary cathode *k* of the tube *a* is connected to a point of this inductance 1 between the ends thereof. One end of the inductance is connected to the anode *d* of tube *a* through a stopping condenser 3 and the other end of inductance 1 is connected to the control electrode *s* of the tube *a* thru a condenser 4. The secondary of the speech transformer *b* is connected across the condenser 4 so that speech current may be impressed on the grid *s* of the tube *a*.

The primary of transformer *b* is connected to a source of speech frequency as illustrated 90 in the drawing. This source of speech frequency may be any old and well known device, such as an ordinary microphone.

The tube *a* receives plate current from a source of direct current *c* operating through the primary of transformer *e* and inductance 5. The secondary of transformer *e* is connected in series with a current limiting device *f* and a telephone *g*.

As explained above, when speech or any 100 signal is impressed upon the grid *s* of tube *a*, the generated oscillations are modulated thereby and are transmitted to the distant station by any suitable and well known means as by an antenna 6 coupled to inductance 1. This speech or other signal

potential causes a corresponding speech or signal in the telephone *g*, which would be very loud and undesirable if no precautions were taken to prevent it. Therefore the current limiting device *f* is used.

When the signal comes in from a distant station, the signal is impressed upon the circuits of the tube *a* from the antenna *6*. Due to the detecting action of said tube, the signal is detected and heard with the telephone *g*.

The circuit shown in Fig. 2 is similar to that shown in Fig. 1, similar reference characters referring to similar elements in these figures. In Fig. 2, however, the vacuum tube *h*, having a cathode *t*, control electrode *u*, and anode *p*, is used as the current limiting device. The grid-filament circuit of tube *h* is connected across the secondary of transformer *e*. The filament *t* and anode *p* of the tube *h* are preferably connected with the filament-heating circuit of the transmitting tube *a* so as to cause the filament-heating battery *i* of the transmitting tube *a* to supply both heating current to the filament *t* of the tube *h* and anode voltage to the plate-filament circuit of said tube. The strength of current which may pass through the tube *h* depends upon the number of electrons emitted from its filament *t*, which, in turn, depends upon the degree to which the filament is heated. Accordingly, the current passing through the tube *h* and the loudness of sound which may be produced in the receiving telephone in the plate-filament circuit of said tube may be readily regulated by suitably controlling the amount of cur-

rent supplied to the filament *t* of the tube *h* from the battery *i*.

The limiting action of tube *h* for large currents and its amplifier action for small currents is obtained by arranging the constants of tube *h* in such manner that for voltages impressed on its grid exceeding a certain predetermined value, the corresponding plate current of tube *h* can become no larger. In other words, the tube *h* saturates at a certain predetermined value of grid voltage.

For impressed grid voltages less than this predetermined value the tube will give its usual amplifier action, thus acting as an amplifier for small voltages.

Having described my invention, what I claim is:

An arrangement for two way telephony comprising a vacuum tube, control electrode and anode circuits associated therewith and regeneratively coupled to form an oscillation generator, an antenna circuit associated with said oscillation generator for radiating energy therefrom or for impressing received energy thereon, a speech modulation circuit coupled to the control electrode circuit of said oscillating vacuum tube, a telephone receiver circuit coupled to the anode circuit of said oscillating vacuum tube, and a second vacuum tube in said telephone receiver circuit arranged for limiting the energy applied to the receiver by saturating at an energy value of the order of magnitude of that flowing upon the reception of normal remotely transmitted signals.

WALTER WURST.
